(57) **CLAIM**

We claim the ornamental design for a snap-together base-board-like accessory for concealing electrical cords, as shown and described.

DESCRIPTION

FIG. 1 is a perspective view of our new design for a snap-together baseboard-like accessory for concealing electrical cords, shown broken away as being of indefinite length; FIG. 2 is a front elevational view thereof; FIG. 3 is a top plan view thereof; FIG. 4 is a bottom plan view thereof; FIG. 5 is an end elevational view thereof, the elevational view of the opposing end being a mirror image thereof; FIG. 6 is a rear elevational view thereof; FIG. 7 is a perspective view showing front and rear portions thereof separated from each other; and, FIG. 8 is a perspective view showing the snap-together baseboard-like accessory for concealing electrical cords in use; the broken lines depict environmental structure for illustrative purposes only and form no part of the claimed design.
